ABSTRACT

A simplified, reduced-size ink-jet type image forming apparatus includes a cap member that covers a nozzle, a pump member that sucks air from inside the cap member, a cap through-hole seal member that seals the through-hole of the cap member, a wiper member that removes the ink adhered to an edge of the nozzle and a carriage position fixing member to which is affixed a recording head transfer carriage, that is moved by a drive motor.

INK-JET TYPE IMAGE FORMING APPARATUS

BACKGROUND OF THE INVENTION

1. Field of Invention

This invention relates to an image forming apparatus, and relates specifically to an ink-jet type image forming apparatus in which an image is formed by ejecting ink onto a recording medium such as paper.

2. Description of Related Art

Conventionally, an ink-jet type image forming apparatus has, for example, a recording medium transfer member that transfers paper and the like in a specified transfer direction and a recording head carriage arranged opposite a transfer path of the recording medium. The carriage is movable in a direction perpendicular to the transfer direction of the recording medium and ejects ink from the nozzles towards the transfer path of the recording medium.

Moreover, a full-color, ink-jet type image apparatus uses a recording head carriage capable of ejecting yellow ink, magenta ink, cyan ink and black ink. Further, the full-color, ink-jet type image apparatus generally comprises a plurality of nozzle components for each respective color and a plurality of ink tanks that supply ink to the nozzle components. Moreover, each of the nozzle components has a plurality of nozzles formed therein and each of the ink tanks is designed to be attachable to and detachable from the recording head carriage.

The ink-jet type image forming apparatus carries the recording medium using the recording medium transfer member. A prescribed image is formed on the recording medium by ejecting ink in accordance with image information while the recording medium is being transferred and the recording head carriage is being moved back-and-forth across the transfer path.

However, this type of ink-jet type image forming apparatus has various problems in maintaining image quality. Poor image quality is associated with the ink itself as well as its ejection from the nozzles to form the image.

Specifically, in the aforementioned ink-jet type image forming apparatus, first, the ink dries out in the nozzle components particularly when no images are being formed. When this condition occurs, the viscosity of the ink increases and, thus, the way the ink ejects from the nozzle components changes so that the desired image is not easily formed.

Second, in the aforementioned ink-jet type image forming apparatus, when foreign material or air enters the nozzles, the ink does not eject properly. Also, when the drying of the ink has progressed, the ink does not eject properly.

Third, in the aforementioned ink-jet type image forming apparatus, there are cases when the ink adheres to the tips of the nozzles specifically around the aperture edge of the nozzle. This occurs because the ink leaks from the nozzles due to a change of environmental conditions. When this condition occurs, the way the ink is ejected changes, and the desired image cannot be easily formed.

In the conventional ink-jet type image forming apparatus described above, these problems have been solved by providing a cap member that protects against the ink from drying out by covering the nozzle when images are not being formed. Also, a pump member is provided that sucks foreign material from the nozzle and a wiper member is provided that removes ink which adheres to the tip of the nozzle.

Moreover, in the aforementioned ink-jet type image forming apparatus, in order to solve these problems without

2

obstructing the back-and-forth motion of the recording head carriage, it is necessary for the cap member to be capable of moving from a position in which the back-and-forth motion is not obstructed to a position in which the nozzles are covered, and to determine these positions. It is also necessary that the position of the pump member can be determined as it is moved from a position in which the back-and-forth motion is not obstructed to a position in which the pump member is connected to the nozzle. It is further necessary to perform the pumping operation when the pump member is connected to the nozzle. It is also necessary that the wiper member be capable of moving from a position in which the back-and-forth motion is not obstructed to a position where it contacts the nozzles. Also, it is necessary to be able to determine these positions of the wiper member.

However, it is difficult to reduce the size of such an apparatus since it is necessary to install each of these maintenance components.

Moreover, in the conventional ink-jet type image forming apparatuses, there are maintenance components that have a reduced size and are designed such that the cap member is connected to the pump and has a combined use for pumping. However, miniaturizing these maintenance components is difficult.

SUMMARY OF THE INVENTION

Therefore, an object of the present invention is to solve the various problems described above in conjunction with providing an ink-jet type image forming apparatus in which it is possible to reduce its size.

In short, the present invention is an ink-jet type image forming apparatus, comprising a recording medium transfer member for transferring a recording medium in a specified transfer direction defining a transfer path, and a recording head carriage that is disposed opposite the transfer path of the recording medium. The recording head carriage is movable in a recording direction perpendicular to the transfer direction of the recording medium, and ejects ink from a nozzle member towards the transfer path of the recording medium while the recording medium is being transferred by the recording medium transfer member and the recording head carriage is being operated in a back-and-forth motion in the recording direction. This forms images on the recording medium by ejecting ink corresponding to image information. The ink-jet type image forming apparatus is provided with a cap member that is arranged so as to be movable while facing a path of motion of the nozzle member and to be able to cover the nozzle member. The cap has through-holes formed therein that communicate with the outside air when the cap is in the covering state. A pump is provided that evacuates the interior of the cap member and a cap through-hole sealing member is provided that is movable with respect to the through-holes and that can seal the through-holes. A wiper member is provided so as to be movable while facing the path of motion of the nozzle member and to remove ink that is adhered to the tip of the nozzle. A carriage position fixing member is provided opposite the path of motion of the recording head carriage and fixes the position of the carriage. Drive means is provided that moves the cap member, the cap through-hole sealing member, the wiper member and carriage position fixing member. The drive means also drives the pump.

In this invention, the nozzle member ejects the ink and generally has a plurality of nozzles. Moreover, it is also acceptable so that the plurality of nozzles eject one type or color of ink, or eject separate colors of ink for each group of nozzles.

The cap member should be arranged so as to be movable opposite the path of motion of the nozzle member and for the cap member to cover the nozzle, with through-holes that communicate with the outside air in a covered state. For example, a concave portion may be formed in a front surface opposite the nozzle, and may comprise a rubber cap in which through-holes that extend through the concave portion to the side surface are formed, an ink holding main body such as a sponge arranged within the concave portion, and a cap case in which the cap is accommodated. The cap case is arranged so as to be movable in a direction in which it contacts with and separates from the nozzle.

Moreover, the covering operation does not refer only to the state in which the perimeter of the nozzle is completely covered by the cap member, but also includes the state in which it is covered to the extent in which it is possible to suitably prevent the drying out of the ink within the interior of the nozzle.

Further, in the ink-jet type image forming apparatus of the type that has a plurality of nozzles, it is acceptable to cover each nozzle with a corresponding cap member or to cover the plurality of nozzles with one cap member.

Moreover, when the nozzle is completely closed to the outside environment by the cap member as the cap member covers the nozzle and when the atmospheric pressure is raised or lowered with respect to the covered nozzle, a pressure difference occurs between ambient pressure and the pressure in the ink tank. The result is that the ink is drawn back within the interior of the nozzle and the ink leaks within the interior of the cap. Therefore, the through-hole is provided to prevent this occurrence.

In the ink-jet type image forming apparatus described above, the cap member is maintained on a carriage which is movable with respect to the recording head carriage transfer path. The cap carriage is arranged opposite the recording head carriage and is also movable in the same direction as the direction of movement of the recording head carriage. Meshing members are provided on each of the cap carriage and the recording head carriage. First, the cap carriage is transferred to a position at which the meshing members can mesh. Then, the recording head carriage is transferred until the meshed members are meshed with each other, and the cap carriage is transferred in the same direction as the recording direction of the recording head carriage to a specified position. Finally, the nozzle should be covered by transferring the cap carriage until the cap member covers the nozzle. By so doing, the cap member can be accurately positioned with respect to the nozzle member and can cover the nozzle member without performing a feed back control based on detecting the position of the nozzle or the cap member or, in short, without performing a complicated control.

The cap through-hole seal member is arranged so as to be movable with respect to the through-hole and seals the through-hole. For example, there is a sealing valve that is arranged to seal the through-hole when the cap carriage moves with the recording head carriage in the same direction as the direction of motion of the recording head carriage. Thus, it is possible to make the structure of the drive means simple since the sealing valve does not need to be moved by the drive means.

The pump member is connected to the cap member and capable of evacuating the inside of the cap member. For example, the structure may comprise a pump that generates negative pressure and a hose that connects the pump and the cap member.

With this structure, it is possible to withdraw solidified ink from the nozzle if the pump is driven while the through-hole is sealed by the sealing valve. Moreover, it is possible to withdraw "waste" ink when the recording head carriage performs a "test firing" if the pump is operated under a condition in which the cap member is separated from the nozzle. Hereafter, the test firing is called a dummy jet.

The wiper member is arranged so as to be movable opposite the path of motion of the nozzle and is able to remove ink which is adhered to an edge of the nozzle. For example, a rubber blade is arranged so as to be able to contact and separate from the path of motion of the nozzle. If the rubber blade contacts the edge of the nozzle, the ink that is adhered to the edge of the nozzle can be removed without moving the rubber blade itself but by moving the recording head carriage. This makes the structure of the drive means simple. Moreover, it is preferable to arrange an absorptive main body, for example, a sponge, to absorb the ink between each nozzle member in the case of a recording head carriage that has several nozzle members. This prevents mixing of ink colors by the rubber blade.

The carriage positioning fixing member is arranged opposite the path of motion of the recording head carriage, and fixes the carriage. For example, the structure may comprise a concave part formed in the recording head carriage and a fixing pin arranged so as to be able to proceed towards and retreat from the concave part.

It is preferable for the drive means to move the cap member, the cap through-hole sealing member, the wiper member and the carriage position fixed member, and to drive the pump member. For example, the drive means may comprise a pulse motor capable of forward and reverse rotation and a cam drive transferring member that transfers the rotation of the pulse motor to each member. In this example, it is preferable to stop the pulse motor at a specified rotating position at a selected positioning time, and to continuously rotate the pulse motor in the forward and reverse directions in the range of the specified rotating angle while driving the pump.

Further, in the ink-jet type image forming apparatus of this invention, the positions of the cap member, the wiper member, the carriage positioning fixing member and the cap through-hole sealing member are determined by the driving means as it moves these components in the advancing and retreating directions opposite the path of motion of the recording head carriage. It is possible to execute various maintenance operations through the drive means.

Moreover, in the ink-jet type image forming apparatus, it is not necessary to install the drive means separately to each member, especially to the pump member and the other members, since the driving means determines the position of each member and also drives the pump.

BRIEF DESCRIPTION OF THE DRAWINGS

FIG. 1 is a perspective view of the ink-jet type image forming apparatus of a preferred embodiment of the present invention;

FIG. 2 is a cross-sectional view of a recording head carriage shown in FIG. 1;

FIG. 3 is a side view of the image forming apparatus of FIG. 1 illustrating movement of a recording medium;

FIG. 4 is a perspective view of a maintenance station;

FIG. 5 is an exploded perspective view of the maintenance station of FIG. 4;

FIG. 6 is a side view of a cap member and a cam drive transfer member;

FIGS. 7A-7D are side views of a cap carriage engaging member and a carriage position fixing member illustrating a capping operation;

FIG. 8 is a side view of the cap carriage engaging member and the carriage position fixing member of FIGS. 7A-7D illustrating a locking operation;

FIG. 9 is a partial cross-sectional side view of a pump member;

FIG. 10A is a partially broken away perspective view of a waste ink conductor;

FIG. 10B is a cross-sectional side view of the waste ink conductor of FIG. 10A;

FIG. 11 is a front, elevation view of the pump;

FIG. 12 is an exploded side view of the pump;

FIGS. 13A-13D are cross-sectional side views of the pump at various pump positions;

FIGS. 14A-14C are cross-sectional side views of the pump at various pump positions;

FIG. 15 is a chart reflecting a suction pressure of the pump as a function of time;

FIGS. 16A-16C are side views of a cap member having a through-hole and disposed in a sequence of cap positions;

FIGS. 17A-17E are partial cross-sectional side views of a right side nozzle disposed in a sequence of right side nozzle positions;

FIGS. 18A-18E are partial cross-sectional views of a left side nozzle disposed in a sequence of left side nozzle positions;

FIG. 19A is a side elevational view of a wiper member;

FIG. 19B is a top plan view of the wiper member in FIG. 19A;

FIG. 20 is a chart illustrating respective conditions of the cap member, the wiper member, the pump, a CRG lock and a main sensor as a function of a cam angle; and

FIG. 21 is a perspective view of a cam drive transfer member.

DETAILED DESCRIPTION OF PREFERRED EMBODIMENTS

Hereafter, a detailed description of embodiments of the image forming apparatus of this invention is provided, based on the attached drawings.

An ink-jet type image forming apparatus 100 relating to a preferred embodiment is shown in FIGS. 1 and 3.

The image forming apparatus 100 has a recording medium transfer member 1 that transfers a recording medium P in a specified direction, a pair of guide members 2 opposite a transfer path T of the record medium P and extending in direction R perpendicular to a transfer direction of the recording medium P, a recording head carriage 3 that is supported by the guide members 2, a maintenance station 4 that is arranged under the guide members 2 and close to the recording medium transfer path T, and a housing that houses all of the aforementioned elements. Image information is sent to the recording head carriage 3 through a signal line 6 which is formed in a flexible base. A home position of the recording head carriage 3 is detected by a home position sensor 7 that is arranged at a position opposite the maintenance station 4.

As shown in FIG. 2, the recording head carriage 3 comprises a head carriage frame 3a arranged so as to be movable on the pair of guide members 2, two nozzle members 3b and 3c that are arranged so as to spray ink lower

than a bottom surface that faces the recording medium transferring path T of the head carriage frame 3a, and two ink tanks 3d and 3e that supply ink to each nozzle member 3b and 3c, and which are attachable to and detachable from the head carriage frame 3a.

Moreover, many nozzles are arranged in each nozzle member 3b and 3c. In the nozzle member 3b, a single color of ink is ejected in response to image information since the ink tank 3d which is connected to the nozzle member 3b supplies black ink. Meanwhile, in the other nozzle member 3c, three colors of ink are able to be ejected in response to the image information, since the ink tank 3e that is connected to the nozzle member 3c supplies yellow ink, magenta ink and cyan ink. In the drawings of this embodiment, several nozzles for each color described above are shown as one nozzle for convenience and, thus, 3f represents a group of several nozzles for black ink, 3g represents a group of several nozzles for yellow, 3h represents a group of several nozzles for magenta and 3i represents a group of several nozzles for cyan.

The ink-jet type image formation apparatus 100, as indicated in FIG. 3, forms the specified image on the recording medium P by transferring the recording medium P with the recording medium transfer member 1 and ejecting ink in accordance with the image information while causing the recording head carriage 3 to move with a back-and-forth motion in the direction R shown in FIG. 1.

The maintenance station 4, as indicated in FIG. 4, comprises a station main body 4a and a waste ink absorbing main body 4b which absorbs and holds the ink discarded from the station main body 4a.

The station main body 4a comprises a unit housing 8 as shown in FIG. 5 and various members attached thereto.

In FIG. 5, an ink carrier 9a is formed by a sponge. A rubber cap member 9b has a concave portion formed therein that holds the ink carrier 9a; and that the cap member 9b also has a through-hole 9f formed therein, shown in FIG. 9, that extends through the concave portion to a side surface of the cap member 9b. A cap case 9c holds the cap member 9b. Moreover, the station main body 4a has two cap member assemblies 9d and 9e, which are held on a cap carriage 10. Each cap member assembly includes one ink carrier 9a, one cap member 9b and one cap case 9c.

The cap carriage 10 has a supporting bottom plate 10a that supports the two cap member assemblies 9d and 9e, a pair of arm structures 10b arranged at both ends of one side of the cap carriage 10, a guide member 10c disposed under the supporting bottom plate 10a, and a supporting member 10d disposed under the supporting bottom plate 10a and adjacent the guide member 10c. As shown in FIG. 6, when the arm structures 10b and guide member 10c are joined to the unit housing 8, the supporting member 10d is connected to an L-shaped arm 11, and the L-shaped arm 11 is able to move up and down (while maintaining its orientation) by being moved by a cam 12a. Hereafter, a member forming the cam 12a is called a cam drive transfer member 12.

Moreover, the cap carriage 10, as indicated in FIGS. 7A-7D, is arranged so as to be movable in a same direction as the direction of movement of the recording head carriage 3, which is hereafter referred to as a left/right direction. A force is applied in a right side direction of the cap carriage 10 by a spring 13.

Moreover, on the recording head carriage 3 are formed two projections 14a and 14b that are positioned next to the two nozzle members 3b and 3c. An engagement pin 14c is arranged on the cap carriage 10 in a position that corre-

sponds to a path of motion of the two projections **14a** and **14b**. A fixing pin **15** is arranged near the engagement pin **14c** so that it is movable in an up-and-down direction in the station main body **4a**. The fixing pin **15**, as indicated in FIG. 8, is biased upwards by a second spring **16** that is inserted between the unit housing **8** and the fixing pin **15**. The fixing pin **15** also engages a channel **12b** of a gear **12g** of the cam drive transferring member **12**, thereby setting the height of the fixing pin **15**.

Then, the station main body raises the cap carriage **10** to a height at which the engagement pin **14c** and the projection **14a** can engage as best shown in FIG. 7B. The engagement pin **14c** and the projection **14a** are then engaged by moving the recording head carriage **3** to the left side, and the cap carriage **10** is moved slightly to the left side as shown in FIG. 7C. Assured capping is possible when the cap carriage **10** is raised and the cap member assemblies **9d** and **9e** are pressed against the nozzle members **3b** and **3c** as shown in FIG. 7D. At the station main body **4a**, when the cap members **9d** and **9e** are pressed against the nozzle members **3b** and **3c**, the fixing pin **15** and the engagement pin **14c** can be inserted between the two projections **14a** and **14b** and the recording head carriage **3** can be fixed by raising the fixed pin **15** to engage the projection **14b**.

Further, in FIGS. 5 and 6, a pump **17a** with two hoses **17b** is connected to each cap member assembly **9d** and **9e**. These elements form a pump assembly **17**. The ink in each cap member assembly **9d** and **9e** can be sucked by the single pump **17a**. Moreover, a waste ink conductor **18** is connected to an exhaust port **23** (shown in FIG. 11) of the pump **17a**, and is structured so that ink is expelled to the waste ink absorptive main body **4b** from the waste ink conductor **18**.

Since the pump **17a** and the waste ink absorbing main body **4b** are arranged in approximately horizontal positions, as indicated in FIG. 10B, a sponge **18b** is arranged at an exhaust port of the waste ink conductor **18** in order to avoid dripping of waste ink when the ink absorptive main body **4b** is exchanged.

As shown in FIG. 11, the pump has two ink absorbing ports **21** and **22** formed in an upper portion of a cylinder **20**. The ink exhaust port **23** is formed in a bottom center part of the cylinder **20** in order to make the ink expel easier. Hereafter, the ink absorbing port **21** that is connected to the right side cap member assembly **9e** is called the right side ink suction port, while the ink suction port **22** that is connected to the left side cap member assembly **9d** is called the left side ink suction port. Moreover, as indicated in FIG. 12, the cylinder **20** receives a piston **90** that is a same size as an inner circumferential surface of the cylinder **20**. The piston comprises a piston head **37** that has a through-hole **26** formed in the center portion thereof and a piston rod **24** that is formed with a diameter **d2** that is smaller than the diameter of the through-hole **26**.

Specifically, the piston head **37** comprises a pair of rubber piston rings **25**, one at each end of the piston head and positioned around the circumference thereof and an ink drain port **27** formed in a side of the piston head **37** between the piston rings **25** and in communication with the through-hole **26**.

The piston rod **24** has a pair of through-hole sealing plates **28** that are sized to seal the through-hole **26** of the piston head **37**. The through-hole sealing plates **28** are arranged and installed at a spacing **l2** that is slightly longer than the length **l1** of the through-hole **26** of the piston head **37**. Moreover, the piston rod **24** is connected to the cam of the cam drive transferring member **12** through a drive transfer arm **19** shown in FIG. 9.

The pump **17a**, as shown in FIGS. 13A-13D, sucks in ink from the right side ink suction port **21**, and also expels ink held in a left side chamber **29** of the cylinder **20** through the through-hole **26** and the ink exhaust port **23** (shown in FIG. 9) via the ink drain port **27**. Moreover, as indicated in FIGS. 14A-14C, the pump sucks ink away from the left side ink suction port **22** as the piston rod **24** is pushed back, and the waste ink which was kept in the right side chamber **30** of the cylinder **20** is expelled from the ink exhaust port **23** (FIG. 9) via the through-hole **26** and the ink drain port **27**.

Moreover, in this embodiment, extremely high pressure can be applied instantly as indicated by the line "a" of FIG. 15 since the right side ink suction port **21** is formed near a center of the cylinder **20** and is arranged so as to communicate with the right side chamber **30** in the cylinder **20** when the piston head **37** is moved to some extent. On the other hand, the left side ink suction port **22** is arranged near an edge of the cylinder **20** and is arranged so as to communicate constantly with the inside of the cylinder **20** so that the low pressure shown by line "b" in FIG. 15 acts for a relatively long period of time.

Next, in FIG. 5, a sealing valve **31** seals the through-hole **9f** of the right side cap member assembly **9e**, and is arranged on the cap carriage **10**. Further, the sealing valve **31**, as indicated in FIGS. 16A-16C, is structured such that the cap carriage **10** is pushed by the recording head carriage **3** and seals the through-hole **9f** by moving to the left side. There is a stopper (not indicated in the figure) which restricts the rotation of the sealing valve **31**, and this maintains the stopped condition even when the sealing valve **31** and the cap carriage **10** are moved. The sealing valve **31** seals the through-hole **9f** by unlocking the restriction of the stopper of the sealing valve **31**.

As shown in FIGS. 17A-17E, the station main body **4a** causes the projection **14a** on the right side to engage with the engagement pin **14c** and covers the black ink nozzle member **3b** with the right side cap member assembly **9e**. Also, the station main body **4a** moves the recording head carriage **3** to the left side and seals the through-hole **9f** of the cap member **9e** on the right side with the seal valve **31** as shown in FIGS. 17A and 16C. By operating the pump **17a** in this state, it is possible to suck foreign material such as ink that has increased in viscosity within the black ink nozzle member **3c**.

Moreover, as shown in FIGS. 18A-18E, the station main body **4a** causes the projection **14b** on the left side to engage with the engagement pin **14c**, and covers the color nozzle **3c** by the cap member assembly **9e**, which is disposed on the right side. The recording head carriage **3** is moved to the left side and seals the through-hole **9f** of the cap member **9e** on the right side with the seal valve **31** as shown in FIG. 18E. By operating the pump **17a** in this state, it is possible to suck foreign material such as ink that has increased in viscosity within the color nozzle member **3c**.

Furthermore, the station main body **4a** positions the recording head carriage **3** so that each of the nozzle members **3b** and **3c** face the respective cap member assemblies **9d** and **9e** as shown in FIG. 17A. Ink is ejected from nozzle members **3b** and **3c** and received at each cap member assembly **9a** and **9e**, and the ink is sucked away as the pump **17a** is operated with the carriage in this state.

Moreover, as shown in FIG. 5, a wiper **32** has a rubber blade. A force is applied by a third spring **33** provided between the station main body **4a** and the wiper **32**. The height of the wiper **32** can be set by pushing down on the wiper **32** through the cam drive transfer member **12**. Also, in FIG. 19B, ink absorption bodies **3j** and **3k** are made from sponges.

Further, as shown FIGS. 19A and 19B, the station main body 4a is moved such that a blade edge of the wiper 32 is positioned in the path of movement of the nozzle members 3b and 3c, and the recording head carriage 3 is moved from the home position to the right side. Thus, the blade edge can contact an edge of each nozzle member 3b and 3c. Moreover, after contacting the edge of each nozzle member, the blade edge is cleaned by the ink absorbing bodies 3j and 3k so that the black ink does not mix with the color ink.

Finally, FIG. 5 illustrates a pulse motor 34, the cam drive transfer member 12, a gear train 35 that transfers the rotation of the pulse motor 34 to the cam drive transfer member 12, and a sensor 36 that detects the rotating phase of the cam drive transfer member 12 via cam member 12h. The drive means includes these elements.

As shown in FIG. 21, the cam drive transfer member 12, as described above, comprises the cam 12a for capping that moves the cap member assemblies 9d, 9e and the like vertically, a channel 12b in a gear 12g that moves the fixing pin 15 vertically, a pumping cam 12d that drives the pump 17a, a wiping cam 12c that moves the wiper 32 vertically, and a cam member 12h for the sensor 36.

Also, the cams are formed so as to drive each respective member against a fixed rotating phase of the cam drive transfer member 12 as shown in FIG. 20. To describe FIG. 20 more specifically, an image forming mode is allotted in which all of the members 9c, 9d, 14c, 15 and 32 are in a retreated position in a rotating range of 350°–10° of the cam, a cap position-determining mode is allotted in which the cap carriage 10 is raised to a half position when in a rotating range of 30°–50°, a carriage stopping mode is allotted in which cap members such as 9c, 9d, 14c and the fixing pin 15 are raised when in a rotating range of 70°–120°, a vacuum mode is allotted in which the pump 17a is driven in a condition in which cap members such as 9c, 9d, 14c and the fixed pin 15 are raised when in a rotating range of 120°–200°, a cap interior space vacuum mode is allotted in which a pump 17a is driven in the condition in which the cap members such as 9c, 9d, 14c and the fixed pin 15 are retreated when in a rotating range of 280°–350°; and, a wiping mode is allotted in which the wiping member 32 is raised when in a rotating range of 320°–330°. The cap interior space vacuum mode is used for sucking the ink discharged from the dummy jet.

Then, in this embodiment, when an image is not being formed, not only is the recording head carriage 3 set in the home position, but it is also set in a carriage stopping mode. Also, when image forming begins, it is set so that it enters into the image forming mode after executing the dummy jet and wiping mode. After image forming has been completed, it is further set so that it goes to the carriage stopping mode after executing the cap position-determining mode. Moreover, experiments were conducted in which, based on a command by the user, it was set so as to execute the vacuum mode.

As a result, in the ink-jet type image forming apparatus, there is no clogging of nozzle members 3b and 3c when they are used for a long period of time and there is no failure of image forming. Also, even if clogging of the nozzle members 3b and 3c were to occur after this period of time, it would be possible to recover immediately.

Moreover, in the ink-jet type image forming apparatus of this invention, with the one pulse motor, it is possible to position-determine the cap members 9c and 9d, the wiper member 32, the carriage position fixing member 15 and the cap through-hole sealing member 31 so that they advance

with respect to the path of motion of the recording head carriage. Also, since the pump 17a is operated, there is no need to install a drive means individually for each member, thus making it possible to greatly reduce the size of the apparatus.

As described above, in the ink-jet method of image forming apparatus of the present invention, because the cap members, the wiper member, the carriage position fixing member and the cap through-hole sealing member are position-determined so that they advance with respect to the path of motion of the recording head carriage, and because the drive means has been provided to operate the pump, there is no need to install a drive means for each individual member. Thus, it is possible to effectively reduce the size of the apparatus, in conjunction with solving each type of problem described above.

What is claimed is:

1. An ink-jet type image forming apparatus, comprising: a recording medium transfer member for transferring a recording medium in a transfer direction defining a transfer path;

a recording head carriage that is disposed opposite the transfer path of the recording medium and is movable in a direction that intersects the transfer direction of the recording medium, and that ejects ink from a nozzle member towards the transfer path of the recording medium and forms an image on the recording medium by ejecting ink corresponding to image information, while the recording medium is transferred by the recording medium transfer member and the recording head carriage is operated in a back-and-forth motion in the recording direction;

a cap member that is arranged so as to be movable while facing the path of motion of said nozzle member and covers the nozzle member;

a wiper member that is movable while facing the path of motion of said nozzle member and removes ink which is adhered to the tip of the nozzle member;

a carriage position fixing member disposed opposite to said recording head carriage moving path, which is engageable with said carriage; and

a single drive source coupled to said cap member and to said wiper member to drive said cap member and said wiper member between a first position where the cap member and the wiper member contact the nozzle member and a second position where the cap member and the wiper member are disposed apart from the nozzle member, said single drive source also coupled to and moving said carriage position fixing member with a back-and-forth motion in a vertical direction which is substantially perpendicular to the transfer direction and the recording direction to selectively place said carriage position fixing member in a path of said recording head carriage.

2. The ink-jet type image forming apparatus of claim 1, further comprising a back-and-forth motion type pump member connected to said cap member that evacuates an inside of the cap member, and wherein said single drive source is coupled to and operates said pump member.

3. The ink-jet type image forming apparatus of claim 2, wherein the single drive source comprises a drive motor having rotational capability and a cam drive transmitting member that transmits the rotation of the drive motor to each member, said drive motor is stopped at a certain angle of rotation during position-determining, and said motor is

11

continuously rotated in a first direction within a range of a selected angular rotation during operation of the pump.

4. The ink-jet type image forming apparatus of claim 1, further comprising a drive shaft that transmits a drive force from the single drive source, a cap member cam for moving the cap member and attached to the drive shaft, and a wiper member cam for moving the wiper member and attached to the drive shaft. 5
5. The ink-jet type image forming apparatus of claim 4, further comprising a cam for operating a pump member and attached to the drive shaft. 10
6. The ink-jet type image forming apparatus of claim 4, further comprising a cam for moving said carriage position fixing member and attached to the drive shaft.
7. The ink-jet type image forming apparatus of claim 1, 15 further comprising a cap carriage that holds the cap member and is arranged opposite the path of motion of the recording head carriage, as well as being arranged facing the recording head carriage and movable in the recording direction; and engaging members provided respectively on the cap carriage and on the recording head carriage so as to mutually engage each other, 20
- wherein when said single drive source moves the cap carriage to a position so that said engaging members can be mutually engaged, and the recording head carriage moves said cap carriage in the same direction as the moving direction of the recording head carriage to a predetermined position, the nozzle member is covered by the single drive source moving said cap carriage so that said cap member covers the nozzle member. 25
8. The ink-jet type image forming apparatus of claim 7, wherein said cap has a through-hole through which outside air passes when the cap covers the nozzle member, and wherein a cap through-hole blocking member is arranged on the cap carriage, and the cap through-hole blocking member blocks the through-hole as the cap carriage is moved by the recording head carriage in the recording direction. 30
9. The ink-jet type image forming apparatus of claim 8, wherein the cap member is arranged to selectively engage the cap through-hole blocking member and the cap member is arranged to be selectively displaced away from the cap through-hole blocking member, 35
- wherein suction of each nozzle member is performed by a pump member when the cap member is engaged with said cap through-hole blocking member. 40
10. An ink-jet type image forming apparatus, comprising: a recording medium drive member that drives a recording medium in a transfer direction defining a transfer path; 45
- a recording head carriage that opposes the transfer path of the recording medium and is movable in a direction that intersects the transfer direction of the recording medium, and that ejects ink from a nozzle member towards the transfer path of the recording medium to form an image on the recording medium by ejecting ink corresponding to image information while the recording medium is transferred by the recording medium drive member and the recording head carriage is operated in a back-and-forth motion in the recording direction; 50
- a cap member that is movable while facing the path of motion of said nozzle member to selectively cover the nozzle member; 55
- a cap carriage that holds the cap member and that is arranged opposite the path of motion of the recording 60
- 65

12

head carriage, the cap carriage also facing the recording head carriage and being movable in the recording direction;

- a first engaging member provided on the cap carriage and a second engaging member provided on the recording head carriage, said first and second engaging members being engageable with each other; and
- drive means for moving said cap member between a first position where the cap member contacts the nozzle member and a second position where the cap member is disposed apart from the nozzle member, wherein when it is desired to cap the nozzle member with the cap member, said drive means first moves the cap carriage to a position where said first and second engaging members can mutually engage each other, then the recording head carriage moves said cap carriage in the same direction as the moving direction of the recording head carriage to a predetermined position, and then the drive means moves the cap carriage towards the nozzle member so that said cap member covers the nozzle member.

11. The ink-jet type image forming apparatus of claim 10, further comprising:

a wiper member that is movable while facing the path of motion of said nozzle member to remove ink which is adhered to the tip of the nozzle member by wiping the nozzle member; and wherein said drive means also moves said wiper member between the first position where the wiper member contacts the nozzle member and the second position where the wiper member is disposed apart from the nozzle member.

12. The ink-jet type image forming apparatus of claim 10, wherein

said cap member has a through-hole through which outside air passes when the cap member covers the nozzle member, and wherein a cap through-hole blocking member is arranged on the cap carriage, and the cap through-hole blocking member blocks the through-hole as the cap carriage is moved by the recording head carriage in the recording direction.

13. The ink-jet type image forming apparatus of claim 12, wherein the cap member is arranged to selectively engage the cap through-hole blocking member and the cap member is arranged to be selectively displaced away from the cap through-hole blocking member,

wherein suction of each nozzle member is performed by a pump member when the cap member is engaged with said cap through-hole blocking member.

14. An ink-jet type image forming apparatus, comprising: a recording medium drive member that drives a recording medium in a transfer direction defining a transfer path; a recording head carriage that opposes the transfer path of the recording medium and is movable in a direction that intersects the transfer direction of the recording medium, and that ejects ink from a nozzle member towards the transfer path of the recording medium to form an image on the recording medium by ejecting ink corresponding to image information while the recording medium is transferred by the recording medium drive member and the recording head carriage is operated in a back-and-forth motion in the recording direction;

a cap member that is movable while facing the path of motion of said nozzle member to selectively cover the nozzle member;

13

a wiper member that is movable while facing the path of motion of said nozzle member to selectively remove ink which is adhered to the tip of the nozzle member by wiping the nozzle member; and

a drive system including: a drive source, a drive shaft coupled to the drive source to transmit a drive force from the drive source, a cap member cam for moving the cap member and attached to the drive shaft, a wiper member cam for moving the wiper member and attached to the drive shaft, and a cam for moving a carriage position fixing member and attached to the drive shaft, wherein the drive source drives said cap member and said wiper member between a first position where the cap member and the wiper member contact the nozzle member and a second position where the cap member and the wiper member are disposed apart from the nozzle member. ⁵ ¹⁰ ¹⁵

15. The ink-jet type image forming apparatus of claim **14**, further comprising:

14

a carriage position fixing member disposed opposite to said recording head carriage moving path, which is engageable with said carriage, wherein said drive source is coupled to said carriage position fixing member by said cam and moves said carriage position fixing member with a back-and-forth motion in a vertical direction which is substantially perpendicular to the transfer direction and the recording direction to selectively place said carriage position fixing member in a path of said recording head carriage.

16. The ink-jet type image forming apparatus of claim **14**, further comprising:

a pump cam for operating the pump member and attached to the drive shaft, and wherein said drive source operates said pump member.
